UNITED STATES PATENT OFFICE.

GEORGE A. HURLEY, OF ROCKLAND, MASSACHUSETTS.

ARCH SUPPORT.

Application filed October 14, 1923. Serial No. 594,802.

This invention relates to shoes, and particularly welt shoes arranged to provide increased support for the arch of the foot.

It is customary to provide an arch-supporting shoe with an inner sole which has an integral lateral extension adapted to fit beneath, and provide increased support for, the arch of the foot. Such an integrally-formed inner sole, however, is relatively expensive as the lateral extension, necessarily, is of the same material as the inner sole, and the shape of the inner sole and integral extension is or may be such that the wastage of cutting the inner soles is increased.

An object of this invention is to provide an arch supporting shoe having an inner sole and a lateral extension so arranged that both may be formed from different pieces and grades of leather.

A further object is to provide a shoe wherein the arch-supporting extension is lasted-in between the upper and inner sole of the shoe and united to the inner sole by the stitching which unites the upper and welt to the inner sole.

A further object is generally to improve the construction of shoes and methods of making them.

Fig. 1 is a plan view of a shoe embodying the invention with the upper partially cut away to illustrate the inner sole and lateral arch-supporting extension.

Fig. 2 is a plan view of the inner sole of the shoe with the lateral extension temporarily attached thereto.

Fig. 3 is a plan view of the bottom face of the inner sole of Fig. 2.

Fig. 4 is a section along line 4—4 of Fig. 3.

Fig. 5 is a sectional detail, in perspective, illustrating more particularly the method of temporarily attaching the lateral extension to the inner sole.

Fig. 6 is a transverse sectional detail of the shoe on the last and illustrating that step in the manufacture of the shoe wherein the upper, welt, extension and inner sole are stitched together.

Fig. 7 is a view similar to Fig. 6 but illustrating a further step in the manufacturing process wherein the edges are trimmed off below the temporary attaching means for the extension and inner sole.

Fig. 8 is a transverse sectional detail of the shoe with the outer sole stitched to the welt.

The completed shoe embodying this invention has the inner sole 10 and the lateral extension 11 which is disposed within the shoe and is adapted to provide increased support for the arch of the foot. The inner sole and extension are formed separately and are secured permanently together in the process of manufacture of the shoe. The extension may be of any suitable or desirable shape and, preferably, is formed with the substantially straight outer edge 12 which also is skived to a thin edge so that it will not distort or bulge the upper. The inner sole and extension may be made of different grades and pieces of leather, for economy of manufacture.

The inner sole 10 is or may be of more or less usual construction and may have the usual lip 14 on its bottom face, to which the upper and welt is adapted to be stitched, and, in accordance with this invention, the lateral inner-sole extension 11 is also attached to said lip.

In the process of manufacture of the shoe embodying the invention the bottom and inner edge of the inner sole is skived to a thin edge as at a, Figs. 4 and 5, along that portion adapted to receive the extension, whereby to provide a smooth and substantially continuous inner face between the inner sole and extension.

The extension 11 is adapted to extend along the inner side of the inner sole preferably from the heel end of the lip 14 to the ball-portion of the inner sole. Said extension is first temporarily attached to the inner sole by staples 15 which are passed through the edge of the extension and the lip 14 of the inner sole; and the staples may be applied in any usual or desirable manner, as by a stapling machine. If desired, an adhesive may be used to secure the extension to the inner sole prior to inserting the staples whereby the better to hold the extension in place during the stapling operation. The staples, or adhesive, or both, are adapted but temporarily to hold the extension in place during the lasting operation and the application of the permanent fastening means and the staples are subsequently removed as a further step in the process.

The inner sole and temporarily-attached extension are then tacked on a last 17, Fig. 6, in a more or less usual manner and the upper 18, and welt 19, are secured to the

inner sole and over the extension by a line of stitching 20 which passes through the welt and upper and extension and the base of the lip 14 of the inner sole and unites all permanently.

The edges of the welt, upper, extension and lip of the inner sole are then trimmed off below the staples 15 which served temporarily to attach the extension to the inner sole, and the extension is left permanently attached to the inner sole by the line of stitching 20.

The shoe may then undergo further manufacturing operations which include stitching the outer sole 22 to the welt as indicated in Fig. 8.

As thus formed, the separate inner sole extension is built into the shoe, and the shoe may be manufactured at a substantial re-

duction in cost as compared to that type of 20 shoe wherein the extension is integral with the inner sole.

I claim:

1. A shoe having an inner sole provided with a lip on its bottom face, an upper, and a separate lateral inner-sole extension applied directly upon said inner sole and the lip thereof, and a line of stitching passed through said upper and extension and lip of said inner sole.

2. An inner sole for shoes having a lip on its bottom face and a separate lateral extension applied directly upon said inner sole and the lip thereof and having means attaching it to said lip.

In testimony whereof, I have signed my name to this specification.

GEORGE A. HURLEY.
